ELEVATING AND LOWERING DEVICE FOR
BALING PRESSES AND THE LIKE

Isidor Spitz, Brooklyn, N. Y., assignor to American-National Bag & Burlap Co., Inc., Brooklyn, N. Y., a corporation of New York

Application January 12, 1949, Serial No. 70,431

4 Claims. (Cl. 100—19)

1

The present invention relates generally to elevating materials to a position adjacent the upper surface of a table-like member and more particularly to a device which may be utilized with a baling press for elevating materials to the level of the press base or table.

Many baling presses or the like have a stationary table-like base portion which has its upper surface positioned some distance above the adjacent floor; a movable press head moves toward and away from the base to compress materials. The materials to be compressed must be lifted up and placed on the base while the head is in a raised position; thereafter the movable head descends and compresses the material. Suitable straps or ties are then placed around the material; the head ascends, and the resulting bale member is removed.

Such presses present the objection of requiring personnel to lift the material up to the level of the base and place it thereon. This is most undesirable due to the expense involved and also by reason of the laborious and tedious nature of the work.

The present invention aims to overcome the above the other difficulties by providing a new and improved device or apparatus which may be used with baling presses and the like for elevating materials to the upper surface of the base, so that they may be easily moved onto the upper surface of the base. The invention further contemplates the provision of a lifting, or lowering, device which may be readily embodied in existing presses.

An object of the present invention is to provide a new and improved lifting or lowering device.

Another object of the invention is to provide a new and improved lifting device or attachment which is particularly adapted to use with baling presses and the like.

Another object is to provide a lifting device which operates automatically during operation of a press.

A still further object of the invention is to provide a lifting or lowering device which may be easily and quickly installed on existing presses.

Other and further objects of the invention will be obvious upon an understanding of the illustrative embodiment about to be described, or will be indicated in the appended claims; and various advantages not referred to herein will occur to one skilled in the art upon employment of the invention in practice.

A preferred embodiment of the invention has

2

been chosen for purposes of illustration and description and is shown in the accompanying drawings, forming a part of the specification, wherein:

5 Fig. 1 is a perspective view showing a preferred embodiment of the invention in a lowered position;

Fig. 2 is a perspective view showing the device of Fig. 1 in a raised or elevated position; and

Fig. 3 is a fragmentary sectional view showing one form of guiding means.

The press itself is shown in dot-dash lines in order to illustrate a baling press or the like in a general manner since the present invention may be used with various types and sizes of presses.

For purposes of convenience the present device is referred to herein as a "lifting" device or attachment but it will be clear, from the description, that it may be used as well for lowering materials. Also, for convenience and clarity of description, the device will be referred to chiefly in connection with a baling press and the pressing of stacks of burlap bags into bales, but its usefulness and applicability to other similar presses and materials will be clear.

Referring more particularly to Fig. 1 of the drawings, there is shown diagrammatically a generally known type of press comprising a base 1 which may project two or three feet, for example, above the surface of the adjacent floor. The upper surface 2 of the press base provides a table-like surface against which material may be compressed. Reciprocable columns 4 extend upwardly above the base 1 and support a press head 5, which descends and ascends with reciprocation of the columns 4. When the columns 4 and head 5 are in elevated position materials may be readily placed into position on the upper surface 2 of the press base 1. As the head 5 descends with the columns 4 materials on the upper surface of the base, for example, a stack 3 of burlap bags, are compressed firmly together. The head 5 may remain in its lowered position long enough for an operator to insert wires, straps or other ties through transverse openings 7 in suitable boards or members at the outer surface of the material 6. Thereafter the columns 4 and press head 5 rise and the resulting tied bale 6 may be pushed off the upper surface 2 of the base. The operation is repeated over and over again as long as stacks of materials are to be formed into bales.

Heretofore it has been necessary to manually lift stacks of material up onto the surface 2 of the press base. With the present invention such

is eliminated by the lifting or elevating device illustrated in the figures. As shown, a pair of spaced arms 10 are attached to the movable press head 5 and extend outwardly therefrom. The arms may be attached in any suitable manner to the press head 5 and any desirable strengthening bracing or brackets (not shown) may be utilized. Bars or connecting members 11 carried adjacent their upper ends by the outwardly extending arms 10, extend downwardly and are connected adjacent their lower ends with a platform-like part 13. The connecting members 11 are shown in the drawings as round bars but they may be formed of any suitable structural members or the like and may be connected with the platform 13 by nuts 15, by welding, or in any other suitable manner.

As the press head 5 ascends and descends the outwardly extending arms 10 attached thereto serve to raise and lower the platform 13 through the intermediation of the connecting members 11.

The length of the connecting member 11 is preferably such that when the press head 5 is in its lowered position the platform 13 will be substantially in alignment with an adjacent floor surface, and such that when the press head is freely elevated a fresh stack of bags or other material may be readily moved from the platform 13 into the space between the base 1 and head 5. In this manner stacks of material may be readily pushed onto the platform 13 and loaded into the machine.

Preferably the connecting members 11 are guided during their reciprocation so that the platform 13 is prevented from freely swinging or banging about. As shown the guiding means comprises structural members 14 having slots or apertures 16 through which extend the connecting members 11. The guiding members 14 may be secured to the adjacent floor by bolts or otherwise.

In operation stacks of burlap bags or other materials to be formed into bales are preferably first placed on a board 8 which has the transversely extending slots 7 therein. The slots 7 are shown facing toward the materials to be compressed so that straps or wires may be passed through the openings in connection with tying the compressed stack together to form a bale. The upper board may be secured to and reciprocate with the press head 5. When a stack of the material is placed on a supporting board the board may be pushed onto the upper surface of the platform 13, the press head 5 then being in lowered position. As the press head 5 elevates, the outwardly extending arms 10 lift the connecting members 11, platform 13 and the stack of material 3 to be baled and places the upper surface of the platform 13 substantially level with the upper surface 2 of the press base 1. In this relationship the stack 3 may be pushed off the platform 13 and onto the upper surface of the press base. Thereafter the press head 5 descends and compresses the material for formation into bales. Simultaneously with descent of the press head 5 the platform 13 is again lowered to the floor. In this relationship another stack of material may be pushed onto the platform 13. When the press head 5 again raises the resulting tied or strapped bale on the upper surface 2 of the press base may be pushed from the surface of the press base to clear it in preparation for receiving another fresh stack of material from the platform 13. Thus the lifting device or attachment operates entirely automa-

tically as the press head 5 ascends and descends.

While the present device is shown at only one side of the press head 5 and is particularly adapted to the elevation of stacks of materials for loading onto the press base 1, it will be clear that a similar device may be provided, if desired, at the opposite side of the press so that materials compressed and tied into bales may be pushed from the upper surface of the press base onto the additional device for lowering. Where a device is used at each side of the press the device at one side serves to elevate fresh stacks and the device at the other side to lower completed bales of material.

The lengths of the connecting members 11, and other dimensions of the attachment device, may of course vary in accordance with the particular press. If desired each of the depending connecting members may be provided with threads 19 for a portion of its length to facilitate use with different presses and under different conditions.

It will be seen that the present invention provides a new and improved attachment or device for lifting stacks of material up to the level of a press base, the materials being readily pushed onto the upper surface of the press base for formation into bales. The device is relatively simple in construction and operation and operates automatically during operation of a baling press itself. The device is sturdy in construction and is well adapted to withstand the rough usage to which it may be subjected.

As various changes may be made in the form, construction and arrangement of the parts herein without departing from the spirit and scope of the invention and without sacrificing any of its advantages, it is to be understood that all matter herein is to be interpreted as illustrative and not in a limiting sense.

Having thus described my invention, I claim:

1. In a baling press having a base with an upper surface normally spaced a fixed distance above a floor and a head above said base reciprocable toward and away from said base for compressing materials between the base and the head upon downward movement of the head, a platform, reciprocable members connected with and normally extending upwardly from said platform for carrying the platform, supporting means connected with said reciprocable members, and attached to a reciprocable portion of the press and extending outwardly therefrom for reciprocating said members and thereby raising and lowering said platform, and means for guiding at least one of said members during reciprocation thereof with said head.

2. In a device of the class described for use with a baling press, a platform, a pair of arms for attachment to a movable portion of the baling press extending over said platform adjacent opposite ends thereof, a plurality of vertically movable supporting members secured to and depending from each of said arms at spaced intervals thereon and having lower portions secured to said platform at spaced intervals thereon, means for varying the effective lengths of said members to thereby adjust the spacing of said platform from said arms, and means for guiding said platform during elevation and lowering thereof comprising members adjacent opposite ends of the platform projecting over said platform and extending at least partly about a supporting member.

3. In a baling press of the class described having a base with an upper surface normally spaced a fixed distance above a floor and a head above said base reciprocable toward and away from said base for compressing materials between the base and the head, means carried by and reciprocable with said head for supporting a platform comprising rods having lengths at least equal to the initial height of a stack of material to be compressed in said baling press, and a platform supported by said means and reciprocable therewith between a platform-loading position below said upper surface of the base and a discharging position adjacent said upper surface of the base for raising materials to said upper surface by upward movement of said head.

4. In a baling press of the class described having a base with an upper surface normally spaced a fixed distance above a floor and a head above said base reciprocable toward and away from said base for compressing materials between the base and the head, means carried by and projecting laterally from said head with respect to its direction of reciprocation and reciprocable with said head for supporting a platform, a plat-

form below said projecting means, and support means secured to said projecting means and platform and reciprocable with the head and projecting means between a platform-loading position below said upper surface of the base and a discharging position adjacent said upper surface of the base for raising materials to said upper surface by upward movement of said head.
